UNITED STATES PATENT OFFICE.

CHARLES E. PIERCE, OF CAMBRIDGE, MASSACHUSETTS.

SET-SCREW GUARD.

SPECIFICATION forming part of Letters Patent No. 761,708, dated June 7, 1904.

Application filed August 3, 1903. Serial No. 167,981. (No model.)

To all whom it may concern:

Be it known that I, CHARLES E. PIERCE, of Cambridge, in the county of Middlesex and State of Massachusetts, have invented certain new and useful Improvements in Set-Screw Guards, of which the following is a specification.

This invention has for its object to provide a simple and effective device adapted for quick and secure application to a projection, such as a set-screw, on a rotary body, such as a shaft, or a collar thereon, to the end that said set-screw may be covered and prevented from all liability of catching the clothing or hair of persons working in the vicinity.

The invention consists in the improvements which I will now proceed to describe and claim.

Of the accompanying drawings, forming a part of this specification, Figure 1 represents a transverse section of a shaft, together with an edge view of a guard embodying my invention, said guard being applied to a set-screw and collar on the shaft. Fig. 2 represents a side elevation of the guard and a corresponding view of the shaft and collar. Fig. 3 represents a perspective view of the guard. Fig. 4 represents an elevation of the inner or under side of the guard. Fig. 5 represents a section on line 5 of Fig. 1. Fig. 6 represents a view similar to Fig. 5, showing the parts in a different position.

The same reference characters indicate the same parts in all the figures.

In the drawings, *a* represents a shaft, and *b* represents a collar thereon, the collar being secured to the shaft by a set-screw *c*. The part *b* may, however, be any rotary member which is secured in place by a set-screw projecting from its periphery.

My improved guard is composed of a single curved strip of resilient material (preferably tempered steel) constituting a bridge extending over the set-screw and comprising a central portion *d* and arms *d' d'*, integral with the central portion, the lower or outer portions of said arms converging inwardly toward each other, so that their ends are separated by a space of less width than the diameter of the collar

or body *b*. The bridge can therefore be engaged with the collar by placing the ends of its arms against the periphery of the collar and applying force tending to move the central portion of the bridge toward the collar, the arms being thus caused to first spring apart until they pass over the center of the collar, the arms then springing inwardly and engaging the collar, as indicated in Fig. 1. The central portion *d* of the bridge is provided with a device for engagement with the set-screw *c*, said device being of such character that when the bridge has been moved to the position shown in Figs. 1 and 2 it cannot be moved edgewise or in a direction parallel with the axis of the shaft because of the engagement of its central portion with the set-screw, the described engagement of the arms *d' d'* with the collar preventing outward movement of the bridge unless a sufficient degree of force is employed to cause the arms *d'* to swing outwardly.

In the present embodiment of my invention I have shown as the means for connecting the central portion of the bridge with the set-screw a strip *e* of flexible material, (preferably sheet metal,) such as copper. One edge of said strip is attached in any suitable way (preferably by a solder connection *e'*) with the central portion *d* of the bridge. The connection *e'* confines only a portion of the edge of the strip *e*, leaving the other portions of the strip free to be bent into engagement with the head of the set-screw. The connection *e'* is preferably arranged between the ends of the strip *e*, so that the strip extends in the form of two arms from the connection *e'*, as clearly shown in Figs. 3 and 4. Before attaching the strip *e* to the bridge I prefer to bend the strip, as shown in Fig. 4, so that it will bear against three sides of the head of the set-screw, the length of the strip being such that its end portions can be bent into engagement with the fourth side of the set-screw head, as shown in Figs. 5 and 6. The meeting ends of the strip may be seamed together by bending each end of the strip backwardly to form a hook and interlocking the two hooks, as indicated in Figs. 5 and 6. The width of the strip

of which the bridge is formed is such that it overhangs the socket formed by the flexible strip *e*, so that said socket does not project from the edges of the bridge. The flexibility 5 of the strip *e* enables it to be conformed to different positions of the head of the set-screw, as indicated in Figs. 5 and 6.

It will be seen that the device when in the condition shown in Fig. 3 can be very quickly 10 engaged with a collar *b* and set-screw *c*, the bridge being first forced onto the collar in the position required to cause the strip *e* to bear upon three sides of the set-screw, after 15 which the ends of the strip *e* are bent to complete the socket.

The bridge forms the outer side of a segmental space at one side of the body *b*, the set-screw projecting into said space and being covered by the central portion of the bridge. 20 I may employ any suitable set-screw-engaging device affixed to the bridge and projecting into said space to coöperate with the resilient arms in holding the guard as a whole firmly 25 in position to guard the set-screw.

25 I claim—

1. A set-screw guard comprising a resilient bridge having a central portion and converging arms formed to engage a cylindrical body, and a set-screw-engaging device affixed to the 30 interior of said central portion.

2. A set-screw guard comprising a resilient bridge having a central portion and converging arms formed to engage a cylindrical body, and a flexible strip affixed to the interior of 35 the said central portion and adapted to be engaged with a set-screw projecting from said body.

3. A set-screw guard comprising a resilient bridge having a central portion and converging arms formed to engage a cylindrical body, and a flexible strip secured at one edge to said 40 central portion and adapted to be engaged

with the head of a set-screw projecting from said body.

4. A set-screw guard comprising a resilient bridge having a central portion and converging arms formed to engage a cylindrical body, and a flexible strip secured at one edge to said central portion and formed to be bent into a socket embracing a set-screw head. 50

5. A set-screw guard comprising a resilient bridge having a central portion and converging arms formed to engage a cylindrical body, and a flexible strip secured at one edge to said central portion and formed to bear on three 55 sides of a set-screw head, said strip being extended so that it may be bent into engagement with another side of said head.

6. A set-screw guard comprising a resilient bridge having a central portion and converging arms formed to engage a cylindrical body, and a flexible strip one edge of which is attached at a point between its ends to said central portion, the said strip having free arms 60 extending from the point of attachment, said arms being adapted to be bent against a set-screw head.

7. A set-screw guard comprising a resilient bridge having a central portion, and resilient converging arms formed to automatically 70 grasp a cylindrical body, said bridge constituting the outer side of a segmental space at one side of said body, and a set-screw-engaging device attached to the central portion of the bridge and projecting into said space, said 75 device and the resilient arms coöperating in holding the central portion of the bridge in position to guard the set-screw.

In testimony whereof I have affixed my signature in presence of two witnesses.

CHARLES E. PIERCE.
